DOOR LOCK CONSTRUCTION

Sigurd Brantingson, Palisades Park, N. J., assignor to Francis Keil & Son, Inc., a corporation of New York

Application January 9, 1935, Serial No. 1,012

7 Claims. (Cl. 70—135)

This invention relates to lock construction and more particularly to lock construction for swinging doors.

One of the objects of this invention is to provide a simple, strong and inexpensive construction for holding and/or locking doors in closed position, more particularly doors of the heavier type or doors subjected to severe usage in practice, as, for example, those of trucks, delivery vehicles, and the like. Another object is to provide a construction of the above-mentioned character which may be quickly and easily installed and, moreover, one which is readily adapted for and installed in connection with either a left-hand door or a right-hand door. Another object is to provide a construction of the above-mentioned character which is capable of great ease of manipulation and capable also of quick and convenient adaptation to the varying requirements of practical use. Another object is to provide a construction of the above-mentioned character in which the locking of the door in closed position may be quickly and easily achieved without impairment of the strength and ruggedness of the construction. Another object is to provide a construction of the above-mentioned character which will be foolproof and dependably under the control, where it is installed in a delivery truck, or the like, of the truck driver or operator. Another object is to provide a construction of the above-mentioned character which is well adapted to meet the varying conditions of hard practical use, particularly such peculiar conditions as are met with in vehicle constructions. Other objects will be in part obvious or in part pointed out hereinafter.

The invention accordingly consists in the features of construction, combinations of elements, and arrangements of parts as will be exemplified 40 in the structure to be hereinafter described and the scope of the application of which will be indicated in the following claims.

In the accompanying drawing in which is shown one of various possible embodiments of my 45 invention,

Figure 1 is a front elevation of the construction as installed;

Figure 2 is a horizontal cross-sectional view 50 on an enlarged scale, as seen along the line 2—2 of Figure 1;

Figure 3 is a vertical sectional view on a similarly enlarged scale, as seen along the line 3—3 of Figure 1, and

Figure 4 is a perspective view on a similarly

enlarged scale, of one of the parts of the construction.

Similar reference characters refer to similar parts throughout the several views of the drawing.

Referring now first to Figures 1 and 2, I have there shown fragmentarily a door 10 and a wall 11 which, for purposes of illustration, may be considered to be part of the enclosure forming a truck body or like vehicle, illustratively a refrigerated vehicle, though it is to be understood that my invention is not limited to its application to vehicles. The door 10 and wall or door frame 11 may be of any desired construction or interfitting relation, illustratively they may be like that indicated in Figure 2, where, as in Figure 1 also, the door is shown in closed position.

The wall 11, adjacent its line of junction with the closed door 10, first has drilled or otherwise formed therethrough a hole 12 and secured to the outer face 11^a of the wall 11 and over the hole 12 is a supporting member generally indicated at 13. Member 13 has an upstanding substantially cylindrical portion 13^a terminating in a base plate 13^b by which the part 13 may be secured, as by screws 14, to the outer face of the wall 11, the base plate portion 13^b being provided with a hole 13^c which may be made to register with the hole 12 in the wall 11 and which is adapted to form a bearing 10 for rotatably supporting a shaft 15. The inner 20 end of the shaft 15 which extends through the hole 12 in the wall 11, is threaded as at 15^a, for a purpose later described in detail, and at its outer end it has rigidly secured thereto or even integrally formed therewith a locking arm 16 25 terminating in a handle 17, the parts 16—17 being of substantial length to give a good leverage 30 for ease of manual actuation.

While hole 13^c in the base portion 13^b (Figure 2) forms an inner bearing for the shaft 15, 40 I provide also an outer bearing for the latter adjacent the lock arm portion 16 thereof and this bearing is formed by a hole 18^a in a member generally indicated at 18 and better shown in perspective in Figure 4. It will be seen to have 45 a ring-like part 18^b of a diameter substantially like the external diameter of the cylindrical portion 13^a of the support 13 and, at diametrically opposite points, it has two legs 18^c and 18^d extending in an axial direction and preferably of 50 substantial extent, being, in cross-section preferably rectangular.

Legs 18^c and 18^d are fitted into and slidably received by external guiding grooves or slots 13^d 55

and 13^e , respectively, in the cylindrical portion 13^a , being likewise diametrically opposed, and being also of substantial extent in the direction of the axis of the part 13^a .

5 The ring-like portion 18^b , therefore, of the member 18 , is by this interfitting of the parts just described, held coaxially with the main supporting member 13 , even though the position of the member 18 relative to the member 13 is 10 changed in the direction of their coinciding axes, due to the interfitting and guiding action and relation of the parts 18^c — 13^d and 18^d — 13^e , and thus adequate support is given the outer (lower, as viewed in Figure 2) end of the shaft 15 .

15 The cylindrical portion 13^a of the main supporting member 13 is bored out, as at 13^f (Figure 2) to receive a helical spring 19 which extends about the shaft 15 and whose opposite ends bottom respectively in the bottom of the bore 13^f 20 and in the spring seat 18^e (Figures 2 and 4) formed in the part 18 ; spring 19 being a compression spring and hence tending always to expand, thereby tending always to force the member 18 and the part 15 — 16 outwardly (downwardly in Figure 2).

25 The threaded end 15^a of the shaft 15 extends through and beyond the wall 11 where, after a washer 20 has been slipped over that end, there is threaded onto it a split nut 21 provided with 30 ears or extensions 21^a , one on each side of the slit or slot therein and adapted to be drawn together by a winged or thumb screw 22 . The nut 21 limits the extent to which the compression spring 19 forces the above-mentioned parts 18 35 and 15 — 16 outwardly.

35 Thereby the lock arm 16 with its handle 17 may be swung about the axis of the shaft 15 , but the member 18 (Figures 1, 2 and 4) is provided with an outwardly extending lug 18^g which 40 is alined with though laterally displaced from the guiding lug 18^e . Accordingly, lug 18^g , when the parts are assembled as above described, is positioned to one side of the axis of the shaft 15 and projects into the plane of swinging movement of the lock arm 16 . The latter is beveled off as at 16^a and 16^b (Figure 1) to provide two 45 appropriately shaped or positioned parts, either of which comes in contact with the lug 18^g , depending upon the direction in which the lock arm 16 is swung. The lug 18^g is thus made to function as a stop arm.

50 Furthermore, these parts are so proportioned that, when the lock arm 16 is swung in counter-clockwise direction from the position shown in Figure 1, to bring the beveled part 16^a into contact with the stop lug 18^g , the center of mass of the parts 16 — 17 falls to the left of the axis of shaft 15 so that the weight of the parts aids in holding them in that position, which is the "open" position. The above-described symmetry of construction, furthermore, makes the parts thus far described properly functional, without change, either for a left-hand door or a right-hand door when installed on a door swinging in a direction opposite from that in which the door 10 of Figures 1 and 2 swings, it is the beveled part 16^b of the lock arm 16 that engages the stop lug 18^g , to function as just described. In either case, furthermore, the frictional action resulting from the spring-pressed engagement of the outer face of the ring portion 18^b (Figure 2) with the inside face of the lock arm 16 and of the locked lock nut 21 with the washer 20 also acts dependably to hold the moving parts in the position to which they have been swung.

55 Adjacent its junction with the handle portion 17 , the lock arm 16 is enlarged and projects rearwardly, as at 16^c (Figures 2 and 3) and it is bored out, as at 16^d , to receive a tumbler casing 23 in which is slidably and non-rotatably mounted a key plug 24 having appropriate tumblers for coaction with those of the casing 23 . The bore 16^d (Figure 3) will be seen not to extend completely through the thickened part 16^c of the lock arm 16 , thereby leaving a rear wall 16^e in 10 which, however, there is formed a hole 16^f alined with the slidable key plug 24 . The latter has a rearward extension (to the right, as viewed in Figure 3), as shown at 25 ; this extension 25 may be integrally formed with the key plug 24 or may be otherwise formed or secured thereto in any desired way, so that it partakes of whatever sliding movement is imparted to the key plug 24 . A spring 29 is interposed between the back wall 16^e and a suitable shoulder on the part 24 and tends to force the latter and hence the extension 25 , which functions as a bolt, in a direction toward the left, as viewed in Figure 3, or downwardly, as viewed in Figure 2, these parts being held assembled within the bore 16^d and to the enlarged portion 16^c by screws 32 that pass through the rear wall 16^e and are threaded into the tumbler casing 23 . The tumbler mechanism and the means for controlling the extent of sliding movement of the key plug 23 and hence of the bolt 25 are not per se my invention and preferably take the form disclosed in detail in the co-pending application of Adam Schoorel, Serial No. 711,367, filed February 15, 1934, now Patent No. 2,050,696, dated Aug. 11, 1936, to which reference for those details is to be made.

50 The enlarged or thickened portion 16^c is provided on its upper side with an elongated lug 16^g and symmetrically positioned with respect thereto but on the lower side is a similar lug 16^h (see Figures 1 and 3).

55 The above described parts coact with a frame generally indicated at 35 and which is secured to the door 10 ; the frame 35 has a plate-like part 35^a shaped substantially as is shown in Figures 1 and 3 to rest flat against the outer face 10^a of the door 10 and to be secured thereto by screws or bolts 36 ; at its lower end (Figure 3) the plate portion 35^a is extended at right angles to provide a horizontal ledge portion 35^b , whence the latter portion is extended downwardly, as at 35^c , to form a handle or grip, the lower end of which (Figure 1) extends inwardly to the face 10^a of the door 10 , where it terminates in a plate-like portion 35^d by which that lower end of the frame 35 may be secured to the door 10 as by the screws or bolt 37 .

60 The upper outer face of the plate portion 35^a (Figure 3) is curved or cam-shaped as at 35^e so that, as the handle 17 with its lock arm 16 is swung from "open" position into the position shown in Figure 1, the inner end of the enlarged part 16^c of the lock arm 16 cams along the curved face 35^e and thereby effecting a tight closing of the door 10 , the degree of tightness of which may be determined or fixed at will by appropriately manipulating the manually operable lock nut 21 (Figure 2). This feature, by the way, facilitates ready and quick readjustment during continued use, particularly to compensate for wear of the interfitting parts of the door and its frame. The lock arm 16 comes to rest on the horizontal ledge portion 35^b of the frame 35 (Figures 1 and 2), the portion 35^b being provided with a recess or slot 35^f into which the lug 16^h of the lock arm 16 75

16 is received where the door swings as the door 10 of Figures 1 and 2 swings, or to receive the lug 16^g where the mechanism is installed on a door that swings in reversed direction.

5 In either case, the hole 16^c in the back wall
16^e (Figure 3) finds itself juxtaposed to or aligned
with the recess 35^f in the plate portion 35^a of the
frame 35 and in readiness to receive the bolt 25.
Accordingly, the key plug 24 may now be actuated
10 against the action of spring 29 to project the
bolt 25 out of the hole 16^c and into the recess 35^f.
This may be achieved with the aid of a key, a
slot for which is shown at 38 (Figure 1) where
the tumbler mechanism above-mentioned locks
15 the key plug 24 in its outward position, or simply
by manually pushing the plug 24 inwardly where
it is desired that the key coat with the tumbler
mechanism only for withdrawal of the bolt 25,
all as described in the above-mentioned co-pend-
20 ing application. Thereby the lug 16^h (Figure 3)
or the lug 16^g in the above-mentioned alternative
installation, is held seated in the recess 35^e and
the lock arm 16 is held against being swung
about the axis of the shaft 15 and away from
25 the seat formed by the right-angled portions 35^a
and 35^b of the frame 35. Subsequent insertion
of the key in the key slot 38 in the key plug 24
coacts with the tumbler mechanism to permit the
now compressed spring 29 to release its stored
30 energy and to force the key plug 24 and hence
the bolt 25 in outward direction, carrying the bolt
25 out of the recess 35^f, and freeing the lock arm
16 for manual swinging about the axis of shaft
15, thereby to permit opening of the door 10.

35 The upper front part of the plate portion 35^a is provided with a recess 35^b (Figure 1), the depth of which (Figure 3) is substantially the same as that of the bolt-receiving recess 35^f, but recess 35^b is open not only at the front of the plate portion 40 35^a but also at the upper-left hand side edge thereof, the latter open portion being, moreover, positioned in the path of arcuate movement of the bolt 25 about the axis of shaft 15.

Accordingly, particularly where the bolt 25 is projectable by simply manually pushing the key plug 24 inwardly, it is desired to prevent the locking of the door 10, the bolt 25, while the lock arm 16 is still out of engagement with the frame 35, is projected into its locking position, so that the subsequent swinging of the lock arm 16 by the handle 17 in clockwise direction, as viewed in Figure 1, brings the now projected bolt 25 into the open-sided recess 35^h, bolt 25 and recess 35^h now acting to stop further movement of the lock arm 16. Due to the shape of the curved or cammed face 35^e and the substantial area of the rear face of the enlarged portion 16^c of the lock arm 16, however, a substantial and adequate camming coaction takes place prior to the above-mentioned stop action of bolt 25 and recess 35^h to tightly hold the door closed and to relieve the bolt 25 from assuming any direct strain in holding the door 10 closed. The weight of the parts 16-17 coupled with the above-described frictional action achieved by the spring 19 (Figure 2) and coacting parts dependably holds the parts in the position just described.

A similar side open recess 35^j (Figure 1) shaped like recess 35^h and symmetrically positioned with respect to it is provided so that the above-described action takes place when the apparatus is mounted to coact with a door swinging oppositely from the direction of swing of the door 10.

The telescopic relation between the ring member 18 and the support 13 and of the shaft 15

with these parts insures, furthermore, that the mechanism may be quickly and easily installed irrespective of the thickness of the wall or door-frame 11 and irrespective of the degree of offset between the front face 10 of the door and the front face 11^a of the part 11, for a simple and quick manipulation of the lock nut 21 speedily brings about an appropriate and proper setting of the parts related to the main support 13 with respect to the part 35 carried by the door 10, all while insuring the dependable achievement of all of the above-described features of action and advantages.

Where the apparatus is employed on vehicles, the above-mentioned action of the spring 19, in achieving a frictional holding of the parts against undesired movement, is of particular advantage and utility in that the moving parts of the mechanism are dependably held against rattling and vibrating due to the vibration of the vehicle itself, and thus, furthermore, long life and dependable action, particularly of the relatively small and delicate tumbler mechanism and immediately coacting parts, are assured.

It will thus be seen that there has been provided in this invention a mechanism in which the objects above set forth, together with many thoroughly practical advantages, are successfully achieved. It will be seen that the construction is of a thoroughly practical character and is well adapted to meet the varying conditions of hard practical use.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In construction of the character described, in combination, a supporting frame structure having means for securing it to a wall adjacent the junction of the edge of the wall with the edge of a door and a member having means for securing it to the door adjacent said junction, a lock arm having a shaft, means for rotatably supporting said shaft comprising bearing means carried by an inner portion of said frame structure and a bearing member for an outer end portion of said shaft, said bearing member having means telescopically relating it to said frame structure, and means for fixing the plane in which said lock arm swings relative to said member, said last-mentioned means comprising spring means interposed between said bearing means and said bearing member and acting to force the latter and said lock arm outwardly of said frame structure and means for fixing the extent to which said spring forces said parts outwardly. 60

to which said spring forces said parts outwardly. 3
2. A construction as claimed in claim 1 in
which the means telescopically relating said bearing
member and said frame structure comprises
opposed guideways on one of said parts and means
on the other of said parts slidably received in 65
said guideways.

3. A construction as claimed in claim 1 in which said bearing member is provided with stop means for limiting the swinging movement of said lock arm, said frame structure and said bearing member having coating means for preventing said bearing member from rotating relative to said frame structure. 70

4. In construction of the character described, in combination, a supporting frame structure hay- 75

ing means for securing it to a wall adjacent the junction of the edge of the wall with the edge of a door and a member having means for securing it to the door adjacent said junction, a lock arm 5 pivotally supported by said frame structure to swing in a plane across the front of said member, said lock arm having a bolt projectable rearwardly thereof and in a direction toward said member, and said member having two recesses 10 spaced along the arc traversed by said bolt as said lock arm swings, the upper of said recesses being open at a side thereof facing toward the path of movement of said bolt, when projected, as the latter is swung toward said member, and the 15 other of said recesses having opposed side walls whereby the bolt may enter it only when projected rearwardly relative to the lock arm.

5. In construction of the character described, in combination, a supporting frame structure 20 having means for securing it to a wall adjacent the junction of the edge of the wall with the edge of a door and a member having means for securing it to the door adjacent said junction, a lock arm pivotally supported by said frame structure 25 to swing in a plane across the front of said member, said lock arm having a bolt projectable rearwardly thereof and in a direction toward said member, and said member having two recesses 30 spaced along the arc described by said bolt as the latter moves with said lock arm, one of said recesses being shaped to receive said bolt only after the lock arm has been swung over the recess and thereafter the bolt is projected rearwardly and the other of said recesses being shaped to receive 35 the bolt after it has already been projected rearwardly of said lock arm and as it is moved with the latter.

6. In construction of the character described, in combination, a supporting frame structure 40 having means for securing it to a wall adjacent the junction of the edge of the wall with the edge of a door and a member having means for securing it to the door adjacent said junction, a lock arm having a shaft extending through said sup- 45 porting frame structure and through said wall

whereby said lock arm may pivot about the axis of said shaft and be swung into or out of operative relation to said member, said lock arm carrying a locking bolt projectable rearwardly thereof and movable toward or away from said member on the door, said member having a front face along and against which said lock arm may be swung, said front face having a recess into which said bolt may be projected, and said member having an open-sided recess spaced along the arc of 10 movement described by said bolt as said lock arm is swung toward or away from the position in which said bolt may enter said first-mentioned recess, and means for setting said lock arm and its bolt respectively to said front face and 15 said recesses and to thereby accommodate the degree of offset between the planes of the wall and door.

7. In construction of the character described, in combination, a supporting frame structure 20 having means for securing it to a wall adjacent the junction of the edge of the wall with the edge of a door and a member having means for securing it to the door adjacent said junction, a lock arm having a shaft extending through said supporting frame structure and through said wall 25 whereby said lock arm may pivot about the axis of said shaft and be swung into or out of operative relation to said member, said member having a cam-shaped front face along which said lock arm, when swung, moves, said front face terminating in a substantially horizontal ledge having a recess therein, said ledge acting to stop the swinging movement of said lock arm and said lock arm having a projecting part adapted to enter 30 the recess in said ledge, and means for setting said lock arm so that, irrespective of the presence or absence of offset between the planes of the wall and door, the plane of movement of said lock arm coincides with the highest point of said cam-shaped front face of said member and the plane 35 of movement of said projecting part is aligned with said recess in said ledge.

SIGURD BRANTINGSON. 45
